UNITED STATES PATENT OFFICE

115,690

DESIGN FOR A FLOOR MACHINE

Fay T. Kent and John Vandenberg, New York,
N. Y.; said Vandenberg assignor to said Kent

Application April 28, 1939, Serial No. 84,652

Term of patent 7 years

To all whom it may concern:

Be it known that we, Fay T. Kent, a resident of the city of New York, county of Queens, State of New York, and John Vandenberg, a resident of the city of New York, county of New York, and State of New York, citizens of the United States, have invented a new, original, and ornamental Design for Floor Machines, of which the following is a specification, reference being had to the accompanying drawing, forming part thereof, in which

The figure is a front perspective view of a floor machine embodying our new design. The dominant features of our design reside in the portions shown in full lines. The rear of the machine is substantially plain in appearance.

We claim:

The ornamental design for a floor machine, substantially as shown and described.

FAY T. KENT.
JOHN VANDENBERG.
